UNITED STATES PATENT OFFICE.

EARNEST WEISS, OF MONROE, WISCONSIN.

STIRRING DEVICE.

No. 913,864.

Specification of Letters Patent.

Patented March 2, 1909.

Application filed November 17, 1908. Serial No. 463,030.

To all whom it may concern:

Be it known that I, EARNEST WEISS, a citizen of the United States, residing at Monroe, in the county of Green and State of Wisconsin, have invented certain new and useful Improvements in Stirring Devices, of which the following is a specification, reference being had to the accompanying drawings.

10 This invention relates to improvements in stirring devices and more particularly those used in making cheese.

The object of the invention is to improve and simplify the construction and operation 15 of devices of this character and thereby render them less expensive, more durable in construction, and convenient and effective in operation.

With the above and other objects in view, 20 the invention consists of the novel features of construction and the combination and arrangement of parts hereinafter fully described and claimed, and illustrated in the accompanying drawings, in which—

25 Figure 1 is a view partly in elevation and partly in section of my improved cheese stirring device; Fig. 2 is a horizontal section with parts in top plan; Fig. 3 is a detail section taken on the plane indicated by the line

30 3—3 in Fig. 1; Fig. 4 is a vertical section taken on the plane indicated by the line 4—4 in Fig. 1; and Fig. 5 is a detail perspective of the clutch device for throwing the stirrer into and out of operation.

35 In the drawings 1 denotes a kettle or other receptacle suspended from an arm or bracket 2 on a pivoted upright 3 so that it may be swung toward and from a fire, stove, or heater of any description. Said upright 40 3 is provided at its top and bottom with pivots 4 arranged in suitable bearings and the arm 2 which projects at right angles or horizontally from it is strengthened by a diagonal brace 5. The kettle is detachably 45 suspended from the outer end of the arm by means of a double or S-shaped hook 6 one end of which is engaged with the beam and the other end with the bail handle of the kettle.

50 7 denotes a suitable stirrer having a stem or shank 8 secured in one end of an angular holder 9 by means of which said stirrer is adjustably connected to a rotating shaft 10. The latter is vertically disposed and mounted 55 for rotation in a bearing tube 11 secured by U-bolts or fastenings 12 to the outer portion

of the arm 2. Said holder 9 has its vertically extending end flared or of gradually increasing width to telescopically receive the lower end of the shaft 10 and also an adjusting 60 wedge 13. The latter and the set screw 14 arranged in the threaded opening in said end of the holder and adapted to have its inner end impinge against the shaft 10 are provided for the purpose of varying the angle 65 of the lower end of the holder 9 with respect to said shaft 10 and, consequently, of the position and path of the stirrer 7 in the kettle.

The stirrer is driven from a main drive shaft 15 arranged in suitable bearings and 70 connected by a sprocket chain gearing 16 to a countershaft 17 also suitably journaled. This countershaft has one of its ends connected by a universal joint 18 and a telescopic or extensible shaft 19 to a vertically 75 disposed shaft 20 arranged upon the pivoted upright 3 and in turn connected by a sprocket chain gearing 21 to the stirrer shaft 10. These driving connections are provided for the purpose of imparting the motion of the 80 countershaft 7 to the stirrer shaft 10 while the arm 2 is being swung to move the kettle toward or from the fire and also operate the stirrer without regard to the position of the kettle with respect to the fire. 85

The sprocket chain 21 passes around a sprocket wheel 22 fixed upon the upper portion of the vertical shaft 20, which latter is journaled in the bearing arms of a bracket 23 secured to one side of a pivoted upright 3. 90 Said chain 21 also passes around a sprocket wheel 24 loosely mounted on the upper portion of the shaft 10 and adapted to be locked to said shaft for rotation therewith by the clutch device shown in Fig. 5. This device 95 comprises a hub 25 formed upon the upper face of the sprocket 24 and provided in its top with a rectangular socket 26 to receive a similar shaped lower end of a clutch member or sleeve 27 formed at its top with a radial 100 flange or finger piece 28 and in its central bore which receives the shaft 10 with a keyway or passage 29 to receive a key 30 provided upon the shaft 10 just above the hub 25. It will be seen upon reference to Fig. 5 105 that when the clutch member 27 is turned upon the shaft to bring its key-way 29 into alignment with the key 30, said member may be slid downwardly upon the shaft so that it will be locked to the latter and so that its 110 lower end will enter the socket 26 to lock the sprocket 24 to the shaft 10 for rotation there-

with; and that when said clutch member 27 is moved upwardly upon the shaft to disengage the key 30 from its key-way 29, and said member 27 is then turned to disalign 5 said parts, as shown in Fig. 5, the member will be supported in its elevated inoperative position by the key 30 and the sprocket 24 will be permitted to rotate independent of the shaft 10.

10 The extensible shaft 19 comprises a tubular section 31 formed with a rectangular bore or passage to receive a similar shaped end 32 of another section 33. The section 31 is connected by the universal joint 18 to the shaft 15 17 and the section 33 is mounted in a bearing arm 34 of a bearing member 35 which is rotatable upon the lower portion of the vertical shaft 20. Said section 33 of the extensible shaft is also provided with a beveled pinion 20 or gear 36 which meshes with a beveled gear 37 upon the shaft 20. The gears 36, 37 are constantly in mesh without regard to the position or movement of the upright 3, the same being permitted by the universal joint 18, 25 the sliding engagement of the sections of the telescopic shaft 19 and the rotation of the bearing 35 on the shaft 20.

The sprocket chain 16 passes around a sprocket wheel 38 fixed to the shaft 15 and 30 around either one of two sprocket wheels 39, 40 fixed to the shaft 17. The chain is shown engaged with the sprocket 39, which latter is smaller than the sprocket 40, the sprocket 40 being employed only when it is desired to 35 drive the stirrer at a very low speed. The driving chain 16 is made very loose and in order to stretch it to a greater or less extent and thereby vary the speed of the shaft 17 with respect to the shaft 15, a pair of flange 40 wheels or idle pulleys 41, 42 are engaged with the inner faces of the opposite stretches of the chain and journaled upon a lever 43 which is pivoted at a point between said pulleys on a pivot 44 and one end of which is provided with a suitable handle 45. By shifting 45 the angle of the lever 43 the chain 16 may be stretched to a greater or less extent so that the speed of the stirrer may be controlled as desired.

50 Having thus described the invention what is claimed is:

1. A device of the character described comprising a support, a receptacle, a rotary shaft carrying a stirrer arranged in said receptacle, 55 a driving element loosely arranged on the shaft and provided with a flat faced socket, a key upon the shaft above the socket, and a clutch member slidably and rotatably mount-

ed upon the shaft and provided with a key-way to receive a key and having a flat faced portion to enter said socket. 60

2. A device of the character described comprising a support, a receptacle, a rotary stirrer shaft, a stirrer, a holder for said stirrer provided with a flared tubular portion to receive the shaft, a set screw in said tubular portion, and a wedge in said tubular portion. 65

3. A device of the character described comprising a pivoted upright having a supporting arm, a receptacle suspended from said arm, a vertical bearing on said arm, a stirrer shaft in said bearing, a stirrer arranged upon the lower end of said shaft, a bearing upon 70 said upright, a vertical shaft in said bearing, driving connections between the vertical shaft and the stirrer shaft, a bearing rotatable upon the vertical shaft, a drive shaft, an extensible shaft having telescopic sections arranged for longitudinal sliding movement with respect to each other but locked 75 for rotation with each other, a universal joint between one section of the extensible shaft and said drive shaft, the other section of said extensible shaft being arranged for rotation in the rotatable bearing on said vertical shaft, and meshing gears upon the last mentioned section of the extensible shaft 80 and said vertical shaft. 85

4. A device of the character described comprising a pivoted upright having a supporting arm, a receptacle suspended from said arm, a vertical bearing on said arm, a stirrer shaft in said bearing, a stirrer arranged upon 90

the lower end of said shaft, a bearing upon said upright, a vertical shaft in said bearing, driving connections between said stirrer shaft and said vertical shaft, a clutch between said driving connections and said stirrer shaft, a rotatable bearing on said vertical shaft, a main drive shaft, a countershaft, sprocket 95 chain gearing between the countershaft and main drive shaft, means for tightening and loosening the chain of said sprocket chain gearing, an extensible shaft having one section mounted in said rotatable bearing, meshing gears on said section of the extensible shaft and said vertical shaft, and a universal joint between the other section of the extensible shaft and said countershaft. 100

105 In testimony whereof I hereunto affix my signature in the presence of two witnesses.
